US00D789381S

(12) **United States Design Patent** (10) **Patent No.:** **US D789,381 S**
Okumura et al. (45) **Date of Patent:** **** Jun. 13, 2017**

(54) **DISPLAY PANEL OR SCREEN WITH
GRAPHICAL USER INTERFACE**

(71) Applicant: **Sony Corporation**, Tokyo (JP)

(72) Inventors: **Mitsuo Okumura**, Tokyo (JP); **Goro Takaki**, Kanagawa (JP); **Satoshi Akagawa**, Tokyo (JP); **Nobuki Furue**, Osaka (JP); **Satoshi Asai**, Saitama (JP); **Hidehiro Komatsu**, Tokyo (JP); **Koji Arai**, Tokyo (JP); **Makoto Niijima**, Saitama (JP); **Shigeya Yasui**, Kanagawa (JP); **Youko Masubuchi**, Tokyo (JP)

(73) Assignee: **SONY CORPORATION**, Tokyo (JP)

(**) Term: **15 Years**

(21) Appl. No.: **29/529,520**

(22) Filed: **Jun. 8, 2015**

Related U.S. Application Data

(60) Continuation of application No. 29/442,763, filed on May 10, 2013, now Pat. No. Des. 736,254, which is

(57) **CLAIM**

The ornamental design for a display panel or screen with graphical user interface, as shown and described.

DESCRIPTION

The FIGURE is a front view of a display panel or screen with graphical user interface showing our new design. The broken lines showing a display panel or screen is provided for the purposes of illustrating portions of the article and forms no part of the claimed design.

1 Claim, 1 Drawing Sheet

Related U.S. Application Data

a continuation of application No. 29/421,029, filed on May 8, 2012, now Pat. No. Des. 682,312, which is a division of application No. 29/311,803, filed on Jun. 26, 2009, now Pat. No. Des. 661,703.
